UNITED STATES PATENT OFFICE.

FREDERICK O. KILGORE, OF SOMERVILLE, MASSACHUSETTS.

INTERNAL-COMBUSTION ENGINE.

1,075,576.

Specification of Letters Patent. Patented Oct. 14, 1913.

Application filed December 23, 1911. Serial No. 866,237.

To all whom it may concern:

Be it known that I, FREDERICK O. KILGORE, a citizen of the United States, residing in Somerville, county of Middlesex, and State of Massachusetts, have invented an Improvement in Internal-Combustion Engines, of which the following description, in connection with the accompanying drawings, is a specification, like letters on the drawings representing like parts.

This invention relates to an internal combustion engine or motor and has for its object to provide a simple, efficient, durable and silent engine or motor of the class described. For this purpose I employ a rotary valve of novel construction as will be described, which is driven from the crank shaft of the motor and controls the admission of explosive medium into the cylinder or cylinders, which may be of the ordinary type now commonly used, but preferably of the construction herein shown, in which the exhaust port is located in the body of such cylinder so as to be uncovered by the piston therein, at or about the time the said piston reaches the end of its stroke away from the rotary valve. The body of each cylinder may also be provided with a second port located below the exhaust port and designed to admit air into the crank case, which in turn is connected with the gas inlet end of the cylinder through the rotary valve as will be described. These and other features of this invention will be pointed out in the claims at the end of this specification.

Figure 1 is a side elevation of one form of internal combustion engine or motor embodying this invention. Fig. 2, a vertical longitudinal section of the motor shown in Fig. 1. Fig. 3, a plan of the motor shown in Fig. 1. Fig. 4, a longitudinal section of the rotary valve shown in Fig. 2. Figs. 5 to 10, inclusive, details in cross section on an enlarged scale taken on the lines 5—5, 6—6, 7—7, 8—8, 9—9, 10—10, Fig. 1, to be referred to.

In the present instance, the invention is shown as embodied in a four cycle engine or motor having four cylinders 20, 21, 22, 23, open at their lower ends and mounted upon a crank case 24 in a manner well understood. The cylinders 20 to 23 inclusive, are provided at their upper ends or heads with ports or openings 25, 26, 27, 28, (see Fig. 2), which may be termed the gas inlet ports, and which are controlled by a rotary valve 29,

located in a casing 30, supported by the said cylinders, to which it is secured by bolts 31 or otherwise. The rotary valve 29 is made hollow as herein shown, and consists of a cylindrical body portion closed at its ends by heads 32 (see Fig. 4), from which extend journals 33, supported upon ball bearings 34 within the valve casing 30, which is provided as represented in Fig. 2 with removable heads 35, 36. The body portion of the rotary valve 29 is provided with slots or openings 37, 38, 39, 40, which are designed to register with the ports 25, 26, 27, 28 in the cylinders 20, 21, 22, 23, respectively, and is further provided with reentrant portions 41, which form external passages or ports 42, one for each of said cylinders, for a purpose as will be described, and further with one or more slots or ports 44. The slots or openings 37, 38, 39, and 40 constitute gas outlet ports and are arranged at different points in the length of the rotary valve, and at different points about the circumference of the said valve, so as to register with the ports or openings 25, 26, 27, 28 in the heads of the cylinders, each gas outlet port registering with the gas inlet port of the cylinder with which it cooperates once in each revolution of the rotary valve, and the external passages 42 are similarly arranged. The slots 44 constitute gas inlet ports for the hollow rotary valve and communicate with a chamber 46 formed by an enlargement 47 of the valve casing, with which the gas supply pipe 48 is connected (see Figs. 3 and 9). The supply pipe 48 is connected in the usual manner with the carburetor or other source of supply (not shown). The external passages 42 are closed to the interior of the hollow rotary valve.

The cylinders 20, 21, 22, 23 are provided with the usual pistons 50, 51, 52, 53, which are connected with the crank shaft 54, and the rotary valve 29 is connected with the crank shaft to be driven thereby. The rotary valve 29 may be connected with the crank shaft by any suitable mechanism. In the present instance, the crank shaft has fast on it a sprocket wheel 56, which is connected by a link chain 57 to a sprocket wheel 58 of twice the size, which is fast on one of the journals 33 of the rotary valve. The driving mechanism referred to may and preferably will be inclosed in a suitable casing 59. In the present instance, the rotary valve casing 30 is provided with two exhaust

ports, only one 60 of which is shown in Fig. 10, one of said exhaust ports being located between the pair of cylinders 20, 21, and the other between the pair of cylinders 22, 23. The exhaust ports 60 are connected by pipes 61, 62, with two main exhaust pipes 63, 64.

Each cylinder of the motor may be provided as herein shown with a single large port or a plurality of smaller ports 70, which are arranged in the body portion of the cylinder so as to be uncovered by the piston in said cylinder, when the said piston is at the end of its stroke away from the head of the cylinder. The ports 70 constitute the exhaust ports for the cylinder and the exhaust ports of the cylinders 20, 21, are connected with the exhaust pipe 63 and the exhaust ports of the cylinders 22, 23 are connected with the exhaust pipe 64. The body portion of each cylinder is further provided, in the present instance, with one or more ports 72, which are located below the exhaust ports 70, so that they are closed by the piston in the cylinder when the exhaust port 70 is uncovered by the piston. The ports 72 admit air into the crank case 24, and this air is designed to be admitted into the cylinder above the piston therein, through a pipe 74, which is connected at one end with the crank case and at its other end with the interior of the valve casing 30. In the present instance, the valve casing is provided with two offset portions 75, 76 (see Fig. 1), which are arranged so as to be located between the two pairs of cylinders and coöperate with the external passages 42 of the rotary valve.

The operation of the motor herein shown may be clearly understood by following the working of the rotary valve with respect to a single cylinder, as for instance the cylinder 20.

Referring to Fig. 2, the piston 50 is at the beginning of its suction stroke, and the rotary valve 29 is about to open its gas outlet port 37 and connect it with the gas inlet port 25 of the cylinder 20 as represented in Fig. 5, so that as the piston moves down in the cylinder 20 and the valve is rotated in the direction of the arrow 80, Fig. 5, fresh gas from the carburetor is drawn through the hollow rotary valve and through the ports 37, 25 into the cylinder above the piston 50. The rotation of the valve 29 is timed with relation to the stroke of the piston so as to close the inlet port 25 to the cylinder after the piston has uncovered the exhaust ports 70. On the return or compression stroke of the piston 50, the fresh gas is compressed as the port 25 is closed by the rotary valve, as shown in Fig. 8. The compressed gas is then fired by the spark plug 81 in the usual manner or in any other desired or suitable manner, and

the piston is driven down again until it uncovers the exhaust ports 70, and at or about the time the exhaust ports are uncovered on the explosion stroke of the piston, the external passage 42 of the rotary valve registers with the mouth of the air chamber 75 and with the gas inlet port 25 of the cylinder, whereupon fresh air under compression is forced from the crank case 24 through the pipe 74 into the chamber 75, thence through the external passage 42 and through the gas inlet port 25 into the cylinder 20 as represented in Fig. 7. The fresh air rushes down into the cylinder and scavenges the same, as it drives all of the burnt or waste gases out through the exhaust ports 70 and into the exhaust pipe 63, said ports and pipe being made large enough to insure all of the gases being driven from the cylinder, thereby leaving only pure or fresh air in the cylinder, which is expelled therefrom on the second upward stroke of the piston or what corresponds to the exhaust stroke of the ordinary four cycle motor. At or about the time the piston begins its second upward stroke, the external passage 42 in the rotary valve 29 uncovers the auxiliary exhaust port 60 and connects the cylinder 20 above the piston with said auxiliary exhaust. On the second upstroke of the piston, the fresh air filling the cylinder above the piston is forced out through the inlet port 25, thence through the passage 42 and through the auxiliary exhaust pipe 61 into the main exhaust pipe 63. At or about the time the piston reaches the end of its second upstroke, the rotary valve cuts off communication between the cylinder 20 and the auxiliary exhaust 60 and opens the port 25, thereby connecting the cylinder with the interior of the hollow rotary valve through the ports 25, 37. The movements of the piston and rotary valve above described are then repeated. On each upstroke of the piston, the air inlet ports 72 in the cylinder are uncovered, and air is admitted into the cylinder below the piston. This air is then forced down into the crank case on the down stroke of the piston and compressed therein, and the air under more or less pressure in the crank case passes through the pipe 74, external passage 42 in the rotary valve, through the port 25 and into the cylinder above the piston. This air carries with it more or less oil from the crank case, and both serve to cool the rotary valve and the cylinder at its hottest part, and further the oil serves to assist in lubricating the rotary valve and the reciprocating piston. Furthermore this cooling effect is augmented by the air on its passage up out of the cylinder through the port 25 and external passage 42 into the auxiliary exhaust pipe 62.

It will be observed, that all of the burnt or hot gases are driven out of the cylinder

through the main exhaust port or ports 70, by the fresh air admitted through the external passage after the manner represented in Fig. 7, and nothing but pure air remains in the cylinder when the piston makes its fourth stroke. As a result, the fresh or unexploded gas drawn into the cylinder on the suction stroke of the piston and compressed on the compression stroke of the same, is not contaminated by burnt or dead gases, and the power of the motor is therefore materially increased, which enables the motor to develop a maximum power with a minimum supply of gas, and thereby obtain an economical running engine or motor. It will further be observed, that the number of parts is reduced to a minimum, and that the rotary valve insures a quiet running motor.

In the present instance, the invention is shown as embodied in a four cylinder four cycle motor, in which a single hollow rotary valve is employed, which is provided with four gas outlet ports to register with the gas inlet ports of the four cylinders, and which is provided with four external ports or passages 42, each of which is made long enough to connect the cylinder with which it co-operates, with the auxiliary exhaust common to the two cylinders of each pair.

In the present instance, the air employed to scavenge the cylinders is taken from the crank case, but it is not desired to limit the invention in this respect, as it may be taken from any suitable source external to the cylinder. In such case the air inlet ports 72 in the cylinder would be omitted.

In the present instance, the hollow rotary valve is shown as used with a cylinder having the exhaust ports in its body portion, and while this arrangement is preferred, it is not desired to limit the invention in this respect, as it could be used to advantage with a cylinder in which the exhaust ports in the cylinder body were omitted, and the auxiliary exhaust pipe 62 employed as the main exhaust after the manner of the ordinary four cycle motor. In this latter case, the advantages attending the use of the hollow rotary valve, would be simplicity in construction, reduction in cost, durability, efficiency and quiet running.

I have herein shown the invention as embodied in one form of motor, but it is not desired to limit the invention to the particular form of motor shown.

I claim—

1. In a motor of the character described, in combination, a cylinder provided with a gas inlet port at one end and with gas outlet and air inlet ports in its body portion, a crank case with which said cylinder communicates, a piston reciprocating in said cylinder and controlling the gas outlet and

air inlet ports in said body portion, a crank shaft in said crank case, means to connect said piston with said crank shaft, a valve casing having a port registering with the gas inlet port of said cylinder, a hollow rotary valve provided with a gas inlet port and with a gas outlet port, and with an external passage non-communicating with the interior of the hollow valve, the gas outlet port and the external passage of said hollow rotary valve being arranged to register with the gas inlet port of said cylinder in the rotation of said valve, a pipe connecting said crank case with said valve casing and co-operating with the external passage in said rotary valve to admit air from the crank case into the cylinder, an auxiliary exhaust port in said valve casing with which said external passage co-operates to connect the same with the said cylinder, and means to connect the rotary valve with said crank shaft, substantially as described.

2. In a motor of the character described, in combination, a cylinder provided with a gas inlet at its upper end and with an exhaust port in its body portion, a crank case with which said cylinder communicates, a piston reciprocating in said cylinder and controlling the said exhaust port, a crank shaft in said case, means to connect said piston with said crank shaft, a valve casing having a port registering with the gas inlet port of said cylinder, a hollow rotary valve located in said casing and provided with a gas inlet port and with a gas outlet port, and with an external passage non-communicating with the interior of said valve, the gas outlet port of said hollow rotary valve in the rotation of the latter registering with the gas inlet port of the cylinder on the downward stroke of the piston to draw explosive mixture therein from the hollow rotary valve, and the external passage of the said valve being connected with the gas inlet port of the cylinder and with the crank case to admit air under pressure into the cylinder from the said crank case on the second down-stroke of said piston, and means to rotate said hollow valve, substantially as described.

3. In a motor of the character described, in combination, a cylinder provided with a gas inlet port at its upper end and with an exhaust port in its body portion, a crank case with which said cylinder communicates, a piston reciprocating in said cylinder and controlling the said exhaust port, a crank shaft in said case, means to connect said piston with said crank shaft, a valve casing having a port registering with the gas inlet port of said cylinder, a hollow rotary valve located in said casing and provided with a gas inlet port and with a gas outlet port, and with an external passage non-communicating with the interior of said valve, the

gas outlet port of said hollow rotary valve in the rotation of the latter registering with the gas inlet port of the cylinder on the downward stroke of the piston to draw explosive mixture therein from the hollow rotary valve, and the external passage of said valve being connected with the gas inlet port of the cylinder to admit air into the cylinder on the second down stroke of the

said piston, and means to rotate said hollow 10 valve, substantially as described.

In testimony whereof, I have signed my name to this specification in the presence of two subscribing witnesses.

FREDERICK O. KILGORE.
